UNITED STATES PATENT OFFICE.

ARCHIE EDGAR LOW, OF OTTAWA, ONTARIO, CANADA.

GROMMET LOCK.

Application filed October 15, 1924. Serial No. 743,834.

To all whom it may concern:

Be it known that I, ARCHIE EDGAR Low, a subject of the King of Great Britain, and resident of the city of Ottawa, in the Province of Ontario and Dominion of Canada, have invented certain new and useful Improvements in Grommet Locks, of which the following is a specification.

This invention relates to improvements in locks, and more particularly to improvements in grommet locks, and the objects of the invention are to provide a simply constructed and effective lock of this character to secure the locking of a bag closed by means of tie cords or ropes passing through grommets, the locking device being attached to the bag itself over one of the grommets.

Further objects are the provision of a lock of this character adapted to securely lock tie ropes or the like used as securing means for any other purpose than tying a bag.

Still further objects are to provide an efficient lock of this character that will not in any way injure or cut the tie cords or ropes with which it engages, and in which the several parts will more satisfactorily perform the various functions required of them, also to provide a lock of this character that can be manufactured and placed on the market at a comparatively low price.

With these and other objects in view the improved lock consists essentially of a grooved cramping bolt and lever adapted to engage the tie-rope of a bag to secure the same in any desired place, the locking means being automatically held in locking position.

Referring now to the drawings, in which like characters of reference indicate corresponding parts in each figure:

Figure 1 is a front elevation of an embodiment of the improved lock mounted on a suitable back plate.

Figure 2 is a similar view with the lock casing removed and showing the lock in open position.

Figure 3 is a similar view to Figure 2, showing the lock closed or in locked position.

Figure 4 is a section through the lock.

Figure 5 is a perspective detail of the grooved cramping bolt and lever.

Figure 6 is a similar view of the key.

Figure 7 is a plan view of a diameter

plate adapted to be used on the inside of a bag and to which the lock-retaining or back plate is riveted through the bag.

Figure 8 is a perspective detail of a modified form of cramping bolt and lever showing the grooves 18 extended to form holes 18^a and 19^b, one above the other.

In the drawings, in which an embodiment of my device is illustrated, 10 indicates the lock casing, with grommet aperture 11 and key aperture 12, and here shown as attached to a plate 14 by means of a retaining screw 13, it being understood that the casing may be secured in any other well-known manner, all as illustrated in Figure 1.

Referring now more particularly to the mechanism as illustrated in Figures 2, 3 and 4, this consists of a vertically arranged bolt 15 rotatably supported in bracket members 16 and 17 screw-secured to the back plate 14. This bolt 15 is grooved on opposite sides at the top at 18 and 19, thus constituting a grooved cramping bolt, and is designed to register with the grommet opening in the back plate and with a similar opening 20 in the supporting bracket 16, both in turn registering with the grommet opening 11 in the casing whereby, as shown in Figure 1, the tie-ropes or cords of the bag will extend through the grooves in the bolt and through the opening in the bolt-supporting bracket, and then through the opening in the lock casing, the bolt 15 being adapted in one position to receive tie-ropes or the like therethrough, and in locked position expanding, as it were, the full diameter of bolt crosswise of the opening, to hold the tie-ropes securely.

Formed integral with the other end of the bolt is an operating lever 21 provided with a suitable handle 22. Substantially midway of its length the bolt 15 is recessed at 9 to engage with a locking bolt 23 operatively supported in a bracket 24 screw-secured at 25 to the back plate, the bolt being automatically held in locking position by a spring 26 engaging at one end with the bolt 23, and the loose end of which is coiled on a suitable pin 27 carried by the back plate. This bolt 23 is reciprocally mounted on the back plate at 28 and is formed with an arm 29 adapted to engage with the wards 30 of a key 21. 32 is a stop member on the bolt 15 adapted to engage with stop means 33 on the lower supporting bracket 16 to limit the travel, in open position, of the bolt 15.

Referring now to the operation of my device, the closing of the bag or the like is accomplished by pulling the tie-ropes 34 and 35 suspended through the lock, as illustrated, to the desired position, securely closing the bag. The lever 21 of the bolt 15 is then placed down to a locking position, as shown in Figure 3, when the bolt 23 will automatically engage with the recess 9 securely locking the bolt and making it impossible to move the bolt or the tie-ropes without unlocking the bolt 23 with the key. This is accomplished by inserting the key and turning it to contact with the arm 29 of the lever 21, thereby releasing it from engagement with the recess 9 and permitting the lever to be raised, as shown in Figure 2, and the tie-ropes free.

The back plate 14, as here illustrated, is formed with a turned-up lower edge or guard at 36 and lugs 37 and 38 for the purpose of detachably holding a dispatch label or the like. The back plate, when the lock is in use in connection with a bag of standard construction such as a post office bag, is riveted to a metal diameter plate, as illustrated in Figure 7, so as to permit the tie ropes passing through the grommet openings on the bag through the grooves of the bolt and through the grommet openings in the face of the lock casing.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. Lock mechanism comprising a grooved cramping expanding bolt formed with a lever at one end and grooved on opposite sides at the other end, said bolt having a recess adapted to be engaged by a locking bolt, means for automatically pressing the bolt towards locking position, and key means for retracting the bolt.

2. In locking mechanism of the character described, a turnably mounted bolt formed with grooves or the like adapted to engage with fastening means, a locking member, and means formed in the bolt designed to engage with said member, and means integral with the bolt for turning it.

3. A lock of the character described comprising, in combination, a back plate having an opening therein, a bolt operatively mounted on said plate, oppositely arranged grooves in the top of said bolt designed to register with said plate opening, lever means on the other end of said shaft, a recess in the bolt, a reciprocally mounted locking bolt adapted to engage with said

recess, and means for automatically pressing the locking bolt towards the locking position, said locking bolt being formed with an arm, a key-receiving pin adjacent said arm adapted to receive the key to engage with said arm to unlock said bolt, stop means for said bolt.

4. In a device of the character described, and in combination with a suitably apertured plate, a grooved cramping bolt rotatably mounted on said plate, a lever integral with said shaft, a recess in said shaft, and a locking bolt adapted to automatically engage with said recess, and a key in combination with means on said locking bolt for reTRACTING the locking bolt.

5. In a lock of the character described, and in combination, a plate having a suitable opening therein, a rotatably mounted bolt formed with oppositely arranged grooves adapted to register, in open position, with said opening, means integral with said bolt whereby the bolt is operated to close the openings in said plate, bracket supporting means for said bolt, an opening in said bracket adapted to register with the grooves in the bolt in open position, a recess in the bolt, a locking bolt operatively mounted on the plate and designed to automatically engage with said recess and means for causing disengagement of the bolt from said recess.

6. A lock suitably mounted on a plate having an opening therein, bracket members on said plate, an opening in one of said brackets registering with the plate opening, a bolt rotatably mounted in said brackets and formed with oppositely arranged grooves designed, in open position, to register with the plate and bracket openings, and in closed position to close said openings, said grooves and openings being adapted to receive therethrough cords or the like, means on said bolt whereby, on said means being moved upwardly, the grooves register with said openings and whereby on the lever being moved downwardly, the full diameter of the bolt registers with the openings to jam the cords, a recess in the bolt, and automatically locking bolt means carried by the plate adapted to engage with said bolt and recess on the lever being moved downwardly, key means for retracting the locking bolt to permit the lever to be moved upwardly, and a stop on said bolt in combination with a stop carried by the supporting brackets.

7. In a lock of the character described, the combination with a back plate having an aperture therein adapted to receive tie cords or the like, of a grooved bolt rotatably mounted on said plate, the grooves adapted to register in open position with the plate opening, supporting means for said bolt, an opening in the supporting means registering with the grooves in said bolt in open

position, a lever integral with said bolt, and means in said bolt adapted to engage with an automatically locking bolt to retain said bolt in position.

- 5 8. In a device of the character described, the combination with suitable supporting means having openings therein adapted to receive tie-ropes or the like, of a combined recessed bolt and lever member operatively 10 carried by the supporting means, said member being designed in open position to register with said openings to receive the tie-ropes, and whereby, on the member being operated downwardly, the tie-ropes are 15 cramped, means for retaining the member in locked position, and means for releasing said member.

9. A lock of the character described comprising, in combination with a supporting 20 plate and a casing, a combined bolt and lever member, bracket supporting means for said member, orifices formed in said member, an opening in said bracket designed to register with the orifices in open position 25 and to receive therethrough tie-ropes, a recess in said member adapted in closed position

to engage with a spring pressed locking bolt operatively mounted on said plate, and key means for operating said bolt locking means, card-retaining means carried by said plate, 30 and means for attaching said plate to a bag or the like.

10. In a device of the character described, the combination with tie-ropes of a card-carrying supporting plate having an opening therein to receive said ropes, and means for locking said ropes comprising a cramping bolt operatively mounted in brackets on said plate, an opening in one of said brackets adapted to register in open position with 40 the bolt and the plate opening to receive therethrough the tie-ropes, lever means carried by the bolt adapted to rotate the shaft to close said openings and jam said tie-ropes, and means for automatically retaining the shaft in locked position, and key 45 means for unlocking the bolt.

In witness whereof I have hereunto set my hand in the presence of a witness.

ARCHIE EDGAR LOW.

Witness:

W. T. CUFFE QUIN.
